US00D957555S

(12) **United States Design Patent** (10) **Patent No.:** **US D957,555 S**
(45) **Date of Patent:** **** Jul. 12, 2022**

(54) **GOLF CLUB HEAD**

(71) Applicant: **KARSTEN MANUFACTURING CORPORATION**, Phoenix, AZ (US)

(72) Inventors: **Evan Greer**, Phoenix, AZ (US);
Xiaojian Chen, Phoenix, AZ (US)

(73) Assignee: **Karsten Manufacturing Corporation**,
Phoenix, AZ (US)

(**) Term: **15 Years**

(21) Appl. No.: **29/751,833**

(22) Filed: **Sep. 23, 2020**

(51) LOC (13) Cl. **21-02**

(52) U.S. Cl.

USPC **D21/752**

(58) **Field of Classification Search**

USPC D21/733, 752, 759

Primary Examiner — Mitchell I. Siegel

(57) **CLAIM**

The ornamental design for a golf club head, as shown and described.

DESCRIPTION

FIG. 1 is a top perspective view of a golf club head;
FIG. 2 is a bottom perspective view of the golf club head of FIG. 1;

FIG. 3 is a top view of the golf club head of FIG. 1;

FIG. 4 is a bottom view of the golf club head of FIG. 1;

FIG. 5 is a front view of the golf club head of FIG. 1;

FIG. 6 is a rear view of the golf club head of FIG. 1;

and,

FIG. 8 is a toe side view of the golf club head of FIG. 1.

The broken lines shown on the drawings form no part of the claimed design.

1 Claim, 5 Drawing Sheets
